UNITED STATES PATENT OFFICE

PERCIVAL ARTHUR BENTLEY, CHARLES FREDERICK MANGER, AND CARLYLE HERBERT WAINWRIGHT, OF LEICESTER, ENGLAND; SAID MANGER AND SAID WAINWRIGHT ASSIGNORS TO SAID BENTLEY

CIRCULAR-KNITTING MACHINE

Application filed June 6, 1927, Serial No. 196,961, and in Great Britain June 19, 1926.

This invention relates to circular knitting machines of the type that is characterized by having superposed needle cylinders within corresponding cam boxes and means to produce relative rotation and rotary reciprocation of the cylinders and cam boxes and by the employment of double-ended needles. Examples of machines of this type are disclosed in the specifications of British Letters Patent Nos. 15008/1900, 24290/1912 and 171,483.

A general object of the present invention is to improve machines of the above type particularly in regard to the devices which are concerned with the feeding of yarn to the needles.

A feature of the invention is an arrangement in a machine of the type hereinbefore specified and having yarn feeding mechanism comprising yarn feeders, of means for moving a feeder adjacent the normal feeding level, then moving the other feeder out of the normal feeding level, then moving the first mentioned feeder into the normal feeding level.

A further feature of the invention is an arrangement in a machine of the type hereinbefore specified and having yarn-feeding mechanism comprising yarn feeders each movable into and out of operative position at the normal feeding level and automatic means for moving one of said feeders into such level and another away therefrom to change the yarn supplied to the needles, in which arrangement the feeders are superposed one upon another and there are means acting automatically to move a feeder, which by reason of such superposition is normally out of the normal feeding level into that level when said feeder is to supply yarn to the needles. Preferably, the feeders are each pivoted to swing about an axis (for example an axis common to the feeders) which is substantially parallel with the axis of the needle cylinders, but obviously they may be pivoted to swing about axes substantially parallel with the axis of the needle cylinders.

A further feature of the invention is the provision in a machine of the type herein-

before specified and having yarn feeders each movable into and out of operative position at the normal feeding level, of mechanism acting automatically when a change is to be made in the supply of yarn to the needles to move a feeder to a position adjacent the normal feeding level from whence it will supply yarn to the needles (to provide the necessary overlap in the work) while yarn is also being supplied thereto by another feeder at the normal feeding level, and then to move said other feeder away from the normal feeding level to cease supply of yarn from it to the needles and to move the first-named feeder into said level.

The invention includes also, as a feature a unitary yarn-feeding device comprising two yarn passages so spaced relatively that when the device is in the normal feeding level the yarn issuing from one of said passages has imparted to it the necessary lead over the yarn issuing from the other passage so as to ensure that one yarn is knitting into the work over the other as a plating yarn.

The above and other features of the invention including an improved yarn cutting and trapping device and certain details of construction, all of which features are pointed out in the appended claiming clauses, will be obvious to those skilled in the art from a consideration of the following description of a preferred construction illustrative of said features and shown in the accompanying drawings.

In the drawings:

Figure 1 is a plan of the parts of a knitting machine with which the invention is particularly concerned.

Figure 2 is an elevation thereof;

Figure 3 is a detail view, in side elevation and partly in section of the yarn feeders shown in Figures 1 and 2;

Figure 4 is an enlarged view of part of Figure 1, to show more clearly the yarn cutting and trapping device and associated parts;

Figure 5 is a section substantially on the line 5—5 of Figure 4;

Figure 6 is a section on the line 6—6 of Figure 5;

Figure 7 is a view like that of Figure 6 but with the parts in a different position; and

5 Figure 8 is a section through a cam shaft of the machine to illustrate a device for effecting angular adjustment of a cam about said shaft.

In the construction illustrated, in front of the normal feeding level of the machine, 10 a pair of levers 10, 12 is mounted one above the other upon a vertically disposed pivot 14, carried by a plate 16 supported on a post 18 projecting upwardly from a stationary part of the machine framework. The 15 upper lever 10 has at its end which is nearer the needle circle, the upper and lower needle cylinders being indicated at 20 and 22 the usual yarn-guiding passage while the lever 12 has its corresponding end forked, 20 each tine of the fork being provided with a yarn-guiding passage one of which, as presently will be described, is used in connection with the feeding of a plating yarn to the needles. To the right hand—i. e. in 25 the direction in which the needles travel when circular knitting is being performed, there is situated in the machine a combined yarn trapper and cutter indicated generally in Figure 1 at 24 the description of which 30 will be given later herein.

Before describing the operating mechanism for the yarn feeders 10, 12 and the trapper, it is deemed convenient now to set forth the movements of these parts and the 35 nature of the work produced.

Assuming that the feeder 10 is operating to feed yarn to the needles, the feeder 12 at this time will be positioned (as in Figure 1) with its feeding end located to the right 40 of the normal feeding level and in proximity to the trapper 24 which holds the end of the yarn (or the ends of both yarns if a plating yarn is to be knitted in also) coming from the feeder 12. With the parts so 45 disposed the fabric produced by the machine will obviously be composed solely of the yarn supplied from the feeder 10.

When a change in the character of the work produced is to be effected—say a colour 50 change—the feeder 12 swings through and slightly beyond the normal feeding level thus laying its yarn or yarns, as the case may be, in position to be taken up by the needles, the trapper 24 still maintaining its 55 hold on the said yarn or yarns. The feeder 12 stays in this position while a few of the needles—say four—are knitting in the yarns from both feeders 10 and 12 to form the necessary lap in the work. The trapper 24 60 next opens to release its hold on the yarn or yarns from the feeder 12 and the feeder 10 moves to the right into or near the position previously occupied by the feeder 12 and in so doing brings its yarn—which of 65 course is still attached to the fabric—be-

tween the jaws of the trapper 24 which now close on the yarn to sever it from the fabric and hold the end thus formed on the part of the yarn leading to the feeder 10. Next following or during such movement of the 70 feeder 10, the feeder 12 is gradually moved to the right into the normal feeding level and the knitting operation proceeds, the fabric being formed by the yarn or yarns issuing only from the feeder 12.

When the knitting is to be restored to the character first herein assumed the positions of the feeders are interchanged and the trapper again operates as above described except of course that the movements above described as imparted to, say, the feeder 10 80 will apply to the feeder 12 and vice versa.

From the foregoing it will be appreciated that with a machine equipped with parts operating as above described, hose may be 85 knitted formed in the main of yarn of one colour but provided with a ring or rings of as many courses wide as is desired of yarn of another colour, such ring or rings appearing, of course, on both sides of the fabric; and further any desired portion of the work may have incorporated in it a plating yarn—say of artificial silk—appearing on 90 one side only of the fabric, the delivery ends of the yarn passages in the feeder 12 being 95 spaced apart a distance sufficient to afford the necessary lead in the plating yarn to bring about this effect.

The mechanism imparting the above-mentioned movements of the feeders and for 100 operating the combined yarn trapper and cutter and the details of construction of the latter will now be described.

Journalled in the machine is a shaft 26 driven from the back shaft 28 of the machine by a pawl and ratchet mechanism controlled as to its time of operation by stops 32 (one of which appears in Figure 2) on the usual pattern chain 34. For this purpose the back shaft carries a cam 36 into and 105 out of range of which a projection 38 on a vertically swinging arm 40 is brought at times by a horizontal swinging movement determined by the stops 32 by means of a rod 42 to the arm 40 from a bell-crank lever 44 operated by such stops 32. To effect the 110 lateral swinging movement of the arm 40, the said arm is pivoted on a bearing block 140 mounted for movement about a vertical axis; the bearing block being so connected to the rod 42 that a turning movement is 115 imparted to it when a stop is encountered by the bell-crank lever 44. The projection 38 is normally out of range of the cam 36 and is brought into the range of the cam for 120 operation thereby at each engagement of a stop such as 42 with the bell-crank lever 44. As the cam 36 engages the projection 38 the latter will be raised and through a tappet 125 rod 46 will swing an arm 48 (pivoted at 49 130

to a bearing support of the shaft 26) that carries the pawl 50 of the pawl and ratchet mechanism already referred to. The arm 48 has an adjusting screw 51 which is maintained in contact with the tappet rod 46 by means of a spring 53. Thus the shaft 26 which carries the ratchet wheel 52 of the pawl and ratchet mechanism is turned to the desired extent so long as the stop 32 on the pattern chain 34 is operative. This shaft 26 also carries a control drum 54 (Figure 1) which is operatively connected with each of the yarn feeders 10, 12. These connections are substantially alike so, for the sake of conciseness, one set only—those relating to the feeder 10 will be described in detail. This set includes a lever 56 which is pivoted at 57 on a part of the machine frame work and which bears against the drum 54 under the action of a spring 58 acting upon a rod 60 projecting from the lever. The lever 56 is coupled to the feeder 10 by a ball-ended strut 62 the ends of which engage, respectively, sockets formed in the feeder 10 and in an adjusting screw 64 threaded in the lever 56, a spring 65 (omitted from Figure 1 but shown in Figure 2) between the feeder and the lever keeping the parts in engagement. The feeder 10 can be adjusted as to its position by the screw 64 and to maintain the adjustment there is provided a set nut 66 (see Figure 2) on the screw 64, which can be locked against the lever 56. The lever 56 in the connections between the control drum and the feeders is actuated by two cam surfaces on the drum, each of said cam surfaces acting on projections 68, 70. These projections may each be formed upon a block 141 adjustable lengthwise of the lever. By adjusting this block or these blocks the timing of the movement of the lever and consequently of the feeder to which it appertains may be varied to vary accordingly the length of the lap in the fabric formed when a change in the yarn supplied to the needles is brought about. By the arrangement of parts above described the movement of the levers which swings the feeders to the left into the knitting location is yieldingly effected, while the feeders are moved positively in the opposite direction by their respective cams on the control drum 54.

The combined yarn trapper and cutter hereinbefore referred to comprises (see Figures 4 and 5) a stationary shear blade 70 with which co-operates a companion shear blade 72 formed on a lever 74 the pivot 76 of which is surrounded by a compression spring 78 which tends to force the blades together laterally to insure a shearing cut on the yarn. To hold the yarn during the cutting and after it has been cut there is attached to the blade 70 a plate 80 which rides against the opposite or non-cutting side of the shear blade 72 and comes into action (see

Figure 7 where the yarn is indicated at 200) as the blades approach to grip the yarn against that side of the shear blade before the blades meet and sever the yarn. Attached to the shear blade 70, conveniently by the same screws by which the plate 80 is secured, is a guide plate 82 which functions to dispose of the cut end of the yarn. The plate 80 has a depending portion 84 (Figure 5) which acts as a guard to prevent movement of the yarn, when introduced into the open shear jaws, beyond a desired point into the bight of the jaws.

The blade 70 is curved outwardly at 86 for the purpose of clearing away loose yarn ends or the like that may tend to enter the machine.

The combined trapper and cutter is closed by a spring 88 acting upon the lever 74 and is opened by another lever 90 (pivoted on the plate 16) one end of which extends under the lever 74 while its other end is connected by a rod 92 (preferably adjustable as to its length as shown in Figure 2) coupling it with a cam lever 94 (Figure 1) pressed by a spring (not shown) against a cam 96 on the shaft 26. This cam is adjustable around the shaft to adjust the timing of the trapper and cutter and to this end has a lateral projection 98 (Figure 8) extending between 90 and engaged by adjusting screws 100 threaded in the two arms of a forked member 102 fixed upon the shaft at one side of the cam.

To check accidental movement of the shaft 26, this shaft has secured to it a disc 104 provided with notches each adapted to be engaged, as the shaft is rotated into its several positions, by a V-block 106 carried by a spring-pressed lever 108.

For the best results it is considered advisable that each of the feeders 10, 12 when at the normal feeding level be stationed at a given level in the machine. This in the present case is assumed to be that of the feeder 10. To bring the feeder 12 to this level when it, in its turn, is at the normal feeding level, the feeders in the present construction are arranged to tip in a plane containing the axis of their pivot 14, the pivot hole in each feeder being slightly enlarged and its edges rounded to permit this tipping movement, and there is a plunger 110 (Figure 3) arranged to lift the feeders, against the action of a spring 112, when the feeder 12 is in the normal feeding level, which plunger is operated by a rocking arm 114 pivoted on the post 18 and actuated at the proper times from a cam 116 on the shaft 26. The arm 114 is connected by a rod 118 with a lever 120 pressed by a spring (not shown) against 125 the cam 116.

In the present construction, the feeders 10, 12 feed the yarn direct to the needles from outside the usual latch guard 122 and not as is usually customary through an aper-

ture in the latch guard, the plate constituting that guard in this case being cut away in such manner as to permit this to occur while at the same time ensuring that the plate performs its latch-guarding function.

5 Although in the particular construction just described there are but two yarn-feeding devices of which one has provision for the feeding of a plating yarn as well as a main yarn, it is to be understood that it is within the scope of the invention to provide more than two yarn feeders any one or more of which may be provided if desired with an additional passage for the feeding of a second yarn. Moreover, if two feeds only are provided each may be arranged to supply but a single yarn.

10 We claim:

1. In a circular knitting machine of the type having superposed needle cylinders within corresponding cam boxes and of the type having means to produce relative rotation and rotary reciprocation of the cylinders and cam boxes and of the type wherein are provided double ended needles, yarn feeding mechanism comprising superposed yarn feeders each movable into and out of operative position at the normal feeding level, means to move a feeder adjacent the normal feeding level, then move the other feeder out of the normal feeding level, and then move the first mentioned feeder into the normal feeding level.

2. In a machine according to claim 1, an arrangement in which the feeders are each pivoted to swing about an axis which is substantially parallel with the axis of the needle cylinders.

3. In a machine according to claim 1, an arrangement in which the feeders are each pivoted to swing about an axis which is substantially parallel with the axis of the needle cylinders, and in which a feeder is arranged to swivel upon its pivot not only about the axis of the latter to move the feeder to a position adjacent the normal feeding level but also in a plane containing that axis to enable the feeder to be tilted from that position into the normal feeding level.

4. In a circular knitting machine of the type having superposed needle cylinders within corresponding cam boxes and of the type having means to produce relative rotation and rotary reciprocation of the cylinders and cam boxes and of the type wherein are employed double-ended needles, yarn-feeding mechanism comprising superposed yarn feeders each movable into and out of operative position at the normal feeding level, said feeders being pivoted to swing about an axis which is substantially parallel with the axis of the needle cylinders and one of said feeders being arranged to swivel upon its pivot not only about the axis of the latter to move it toward the circumferential

feeding position but also in a plane containing that axis to enable it to be placed in the normal feeding level and mechanism acting automatically when a change is to be made in the supply of yarn to the needles to swing a feeder about its pivotal axis into a position adjacent the normal feeding level from whence it will supply yarn to the needles to provide the necessary overlap in the work while yarn is also being supplied thereto by another feeder at the normal feeding level, and then to move said other feeder away from the normal feeding level to cease supply of yarn from it to the needles and to move the first-named feeder in a plane containing its axis into said level.

5. In a circular knitting machine of the type having superposed needle cylinders within corresponding cam boxes and of the type having means to produce relative rotation and rotary reciprocation of the cylinders and cam boxes and of the type wherein are employed double-ended needles, yarn-feeding mechanism comprising yarn feeders each movable into and out of operative position at the normal feeding level, said feeders being pivoted to swing about an axis common to the feeders which axis is substantially parallel with the axis of the needle cylinders, one of such feeders which by reason of such superposition is normally out of the level of the normal feeding level, and mechanism acting automatically when a change is to be made in the supply of yarn to the needles to move a feeder to a position adjacent the normal feeding level from whence it will supply yarn to the needles to provide the necessary overlap in the work while yarn is also being supplied thereto by another feeder at the normal feeding level, and then to move said other feeder away from the normal feeding level to cease supply of yarn from it to the needles and to move the first-named feeder into said level and into the position just vacated by the other feeder.

10 In testimony whereof we have signed our names to this specification.
